UNITED STATES PATENT OFFICE.

OTTO J. GEHRKE, OF TACOMA, NEW YORK.

CIRCULAR-SAW TABLE.

1,304,872.

Specification of Letters Patent. Patented May 27, 1919.

Application filed August 20, 1917. Serial No. 187,317.

To all whom it may concern:

Be it known that I, OTTO J. GEHRKE, a citizen of the United States, residing at Tacoma, in the county of Delaware, State of New York, have invented certain new and useful Improvements in Circular-Saw Tables; and I do hereby declare the following to be a full, clear, and exact description of the invention, such as will enable others skilled in the art to which it appertains to make and use the same.

One object of the present invention is to provide a saw table structure which will be such as to accommodate pieces of lumber of different diameters or widths, as well as of different lengths.

In the construction of the invention for the accommodation of material of considerable length, it is an object to provide, in connection with work supporting portions which are movable to bring work into and out of engagement with the saw, additional work supporting portions disposed to receive and support material which may project beyond the table proper, these supplemental supporting portions being movable to correspond to movement of the material when the latter is operated upon.

It is another object of the invention to provide means for holding material upon the supporting portions and for moving the supporting portions to properly position the material with respect to the saw.

Other objects and advantages will be apparent from the following description:

In the drawings,

Figure 1 is a side elevation of the complete saw table.

Fig. 2 is a top plan.

Fig. 3 is a longitudinal section taken on line 3—3 of Fig. 2.

Fig. 4 is a transverse section taken on line 4—4 of Fig. 2.

Fig. 5 is a vertical section taken on line 5—5 of Fig. 4.

Fig. 6 is an end view.

Fig. 7 is a fragmentary end view showing the work holding carriage moved toward the saw, so that the hinged board is brought into holding engagement with a small piece of work.

Referring particularly to the accompanying drawings 10 represents a frame on one end of which is mounted a table 11, supports 12 being carried by the table for supporting

the shaft 13 of the circular saw 14, which extends transversely of the frame. Extending transversely of the frame 10 are the beams 15 on which are secured the metal strips 16, whereby tracks are formed. A frame including parallel side members 17, extending longitudinally of the frame 10, and the connecting transverse members 18, is disposed over the frame 10, and is provided with the depending brackets 19 in which are mounted the rollers or wheels 20 for rolling engagement on the metal strips of the before-mentioned tracks. Disposed transversely between the side members of the last-named frame, and journaled at their ends in the said side members, are a plurality of parallel rollers 21. On these rollers the piece of work to be sawed is placed and arranged to be easily fed toward the saw. The transverse members 18 extend beyond one of the side members 17, and on one of said extensions there is mounted a block 23 having an upper downwardly and inwardly inclined face 24. The adjacent side member 17 has hinged thereto a board 25 which is arranged to rest on the said inclined face of the block 23 whereby said board will be held in an inclined position, and limited in its outward swinging movement. Hook-shaped straps 26 are carried by the transverse members 18 and engage with the tracks to hold the frame from movement from said tracks. The side portions of the brackets 19 also depend on opposite sides of the tracks to insure the proper engagement of the rollers with the tracks.

At the end of the frame 10, opposite to that which carries the saw, are mounted a pair of brackets 27 for the removable reception of the hooked ends of a pair of arms 28 carried by a vertical frame 29, disposed at that end of the frame 10. This frame 29 includes a shaft 30 in the upper portion thereof, which extends parallel with the transverse dimension of the frame, and mounted for rotatable as well as longitudinal slideable movement on said shaft is a flanged roller 31 on which one end of the work is arranged to rest and slide as said work is moved toward the saw for cutting and advanced as the saw cuts through the work.

Mounted on the frame 10, between the table 11 and the adjacent end of the movable frame which supports the work, is a bifurcated bracket 32, and pivotally mounted in

this bracket is a curved lever 33, the portion which is pivoted to the bracket being provided with an arcuate slot, as at 34 for the reception of the pivot of said lever. Thus 5 the lever is slidably as well as pivotally connected to the bracket. Pivotally mounted on the said lever is a curved hook member 35, the outer end being formed with a point 36 which is adapted to be driven into work 10 disposed upon the rollers 21. This structure is best shown in Fig. 4, from which it will be seen that the outer or handle end of the lever 33 may be manually operated to shift it upwardly, which will initially force 15 the point 36 of the dog 35 into work with which it may be engaged, and that further upward movement of the outer end of the lever will move this lever slidably with respect to its point of pivotal mounting. By 20 reason of the arcuate formation of the lever, its sliding movement with respect to its pivot point will shift the dog 35 toward the saw 14, carrying with it the work engaged by the dog, and since the work is frictionally 25 engaged upon the rollers 21, these rollers and the frame by which they are carried are shifted laterally upon the frame 10, and the work is brought into engagement with the saw.

30 When small pieces of work are being sawed, that is pieces of diameters too small to permit the use of the lever 33 and the dog 35 the hinged side of the movable table or frame is swung inwardly and pressed downwardly against the work to hold the work in proper position against the saw and to prevent slipping thereof and the movable frame is shifted by pressing against the board. 35 This is clearly shown in Fig. 7.

40 The roller 31 is particularly adapted to support the outer end of a piece of work which is of greater length than the supporting frame or table, the slidable movement of the roller permitting it to move with the 45 work as the latter is moved transversely of the saw during the cutting operation. Correspondingly, the rotatable mounting of the roller 31 permits it to revolve as the work is moved longitudinally for the making of 50 a second cut. The flanges of the roller, of course, retain the work thereon against lateral displacement.

What is claimed is:

1. A work supporting and feeding device 55 for saw tables, including work supporting portions movable to bring work into and out of engagement with a saw and supplemental work supporting means shiftable correspondingly to the movement of the said

supporting portions and disposed to receive 60 thereupon work supported by said supporting portions and movable by work engaged thereupon with the said work supporting portions.

2. A work supporting and feeding device 65 for saw tables including a frame, work supporting portions movably mounted upon the frame, and means carried by the frame for holding work upon the work supporting portions and for moving such work supporting 70 portions with respect to the frame.

3. A work supporting and feeding device 75 for saw tables, including a frame, a second frame shiftable upon the first frame, work supporting rollers journaled in the second frame, a supplemental frame, and a work supporting roller mounted in the supplemental frame for rotation and for sliding movement.

4. A work supporting and feeding device 80 for saw tables, including a frame, a second frame shiftable upon the first frame, work supporting rollers journaled in the second frame, a supplemental frame, a shaft mounted in the supplemental frame and a work 85 supporting roller journaled upon the shaft and slidably longitudinally thereupon.

5. A work supporting and feeding device 90 for saw tables including a frame, a second frame shiftable upon the first frame, work supporting rollers journaled in the second frame, a supplemental work supporting roller located beyond the second frame at one end thereof and mounted for sliding movement corresponding to the movement 95 of the second frame upon the first frame and means carried by the first frame for holding work upon the roller and for movement of such work to shift the second frame.

6. In a work supporting and feeding device 100 for saw tables, the combination with a frame, of a second frame shiftable upon the first frame, work supporting elements carried by the second frame, a lever slidably and pivotally connected with the first frame, and a dog carried by the lever, said lever being shiftable in its pivotal movement to engage the dog with work disposed upon the work supporting portions, and being shiftable in its sliding movement to move such work and the second frame with respect to the first frame.

In testimony whereof, I affix my signature in the presence of two witnesses.

OTTO J. GEHRKE.
